11 Claims. (Cl. 4—6)

This application relates to an improved device for therapeutic care and treatment of the perineal, rectal or genital areas of the human body.

The invention is more particularly concerned with a device for use in the post-operative care and treatment of patients who have undergone surgery, such as hemorrhoidectomy or other operative procedure on the rectum, anus, or other perineal regions of the body, as well as for use in non-surgical therapy and hygienic care of these areas. The therapeutic care and treatment normally requires bathing of the area in warm water, which may or may not be medicated, for relatively lengthy periods several times each day, to minimize pain and promote healing. This post-operative treatment is usually required to be performed for a number of days following surgery. In the case of a hemorrhoidectomy, for example, the practice is generally for the patient to utilize such post-operative treatment for five to twenty days immediately after the surgery.

In hospitals, this post-operative therapy is customarily performed in so-called sitz baths installed as permanent fixtures, or by means of a mobile sitz bath. The permanently installed sitz baths are not only costly in themselves, but also entail provision of a separate room to accommodate the required number of them. The mobile devices generally consist of a metal framework in the shape of a chair, on which is fixedly or removably mounted a pan into which water may be poured and into which the perineal regions of the body will extend when the patient is seated in the chair. In the more desirable of these devices, they are fashioned also for mounting a heater assembly thereon, in order to maintain the water in the pan at a suitable temperature before the patient is seated on the chair for the treatment.

Although the mobile sitz bath devices used in hospitals for these post-operative procedures adequately serve the therapeutic purposes of the treatment, they are expensive to the hospitals, not only in terms of their initial relatively high cost (of the order of several hundred dollars each) but also in terms of the labor required for cleaning and sterilizing the seat and the pan, as well as of the space requirements they impose upon the hospitals for storing them during periods when they are not in actual use by a patient.

Patients who have undergone surgery of the type referred to above are nowadays permitted and encouraged to leave the hospital within two days, or at most several days, following the surgery. Hence, the post-operative care of the affected areas for relieving pain and promoting full recovery, requires the patient to carry on this treatment at home.

For this purpose, the patient may sit in a tub of warm water for the prescribed period of time, several times a day. This procedure is troublesome and objectionable to most patients, as it requires the patient to undress and dress for each such period of treatment. Furthermore, many people frequently suffer debilitating or other ill

2

effects from relatively long periods of contact with water at the elevated temperature used.

For carrying on such treatment by the patient at home, there have heretofore been proposed several forms of sitz baths, consisting essentially of a pan or basin for holding a supply of water, and arranged to be supported, by an outwardly extending flange thereon, upon the upper edge of the toilet bowl, or upon the top of the toilet seat, so that a considerable portion of the basin will extend down into the toilet bowl.

Portable sitz baths of this type are shown in the patents to Oliver, Nos. 2,427,807 and 2,450,607. In the first of these patents, the basin is provided at its front and rear ends with spillways so that when the basin is suspended from a toilet seat, liquid that might otherwise be splashed over the sides of the basin is directed by way of the spillways into the toilet bowl. In Patent No. 2,450,607, the basin is held within an annular ring formed to rest on the seat and having a depending flange to provide an annular channel between the outer surface of the basin and the inner surface of the flange, for conveying the overflow from the basin directly into the toilet bowl.

Another form of portable sitz bath adapted for use with a conventional toilet bowl by supporting the same from the upper edge of the toilet bowl or from the toilet seat, is disclosed in the patent to Gruber No. 2,426,303. In the device of the Gruber patent, provision is made for maintaining the water in the basin at a desired temperature, by affixing a water jacket to the exterior of the basin so as to surround and enclose the lower end thereof and arranged to be supplied with hot or cold water through a flexible tube connected to a faucet of a conventional bathroom lavatory, the water jacket being arranged so as to permit excess water supplied to the jacket to overflow directly into the toilet bowl. Access of the outlet end of the flexible tube to the water jacket is provided by openings formed in the flange by which the basin is supported on the toilet bowl, these openings extending a short distance downwardly from the flange into the basin at the front and rear thereof. These openings also provide for the overflow of the liquid from the basin proper directly into the toilet bowl.

While portable sitz baths of the type shown in the above-mentioned patents would obviously be less costly than the mobile devices currently in use by hospitals, and can be merely lifted from the toilet bowl after each use and stored in a space of a small area, they do not meet other requirements essential to provide a practical form of device for use either in hospitals or in homes, for performing the therapeutic procedures referred to above. Thus, among other things, it is essential that such devices have provision whereby the patient can, while in seated position on the device, conveniently control the supply of water to the basin, and its maintenance therein at a predetermined fixed level and at a desired temperature during the soaking period. Desirable, also, are means for enabling the patient, at the conclusion of the soaking, and while still in the seated position occupied during the soaking period, to drain the water from the bath, and thereby avoid the annoyance of having water from the perineal regions trickling down along the thighs and legs when the patient arises from the sitting position. It is desirable also that the introduction of the water into the basin be arranged so as to promote rapid mixing of incoming water with that contained in the basin and so as to avoid impingement of the incoming stream upon the patient's buttocks. Such an arrangement has the further advantage of precluding the possibility of water splashing and wetting the clothing of the patient while sitting on the basin.

Our invention is concerned particularly with a portable sitz bath for use in therapy and other care of the types

set forth, constructed to meet the above-mentioned requirements and otherwise to avoid the shortcomings and disadvantages of the stationary, mobile and portable sitz baths heretofore proposed.

The invention also aims to provide a sitz bath of this character, which will lend itself to use either in hospitals or homes and which may be inexpensively fabricated from various materials suitable for the purpose.

According to our invention, there is provided a sitz bath having valve means located thereon within reach of the patient's hand while occupying a sitting position with the perineal regions submerged in the bath and which enables the patient selectively to supply water to the basin in regulated flow or to cause the flow of water from the source of supply to be diverted so as to discharge directly into the toilet bowl. The valve means serves also, in certain embodiments of the invention, as a means for draining the contents of the sitz bath directly into the toilet bowl at the conclusion of the desired period of immersion and prior to arising from the sitting position occupied by the patient during the period of soaking in the bath.

By providing the sitz bath with means which enable the patient, while in the sitting position, to admit water at a controllable rate or to stop the flow of water to the bath, at any time during the soaking period in which the perineal regions are immersed in the bath, the temperature of the water in the bath may be adjusted by the patient as needed during the soaking period. Also, by providing for the entry of the water into the bath at a point adjacent its bottom, the patient is enabled, by continuing the flow of the water into the basin while seated thereon, to gain the soothing and other beneficial effects of having the perineal areas immersed in water that is in a state of motion, as compared to a quiescent body of water.

The portable sitz bath of the invention may be connected by a flexible hose with a water faucet of a lavatory or other bathroom fixture. In order to comply with the sanitary codes in effect in many communities with respect to the connection of plumbing fixtures to the water supply system, a suitable anti-siphoning device may be interposed between the faucet and the inlet of the valve means, to insure against back siphonage of water from the bath to the water supply system.

These and other purposes of the invention, and the numerous practical advantages thereof, will be more readily understood from the detailed description given herebelow, and from the accompanying drawings illustrating several embodiments and modifications thereof.

In the drawings:

Fig. 1 is a view, in perspective, of a portion of a conventional toilet bowl, having the sitz bath embodying the present invention disposed in operative position thereon, and illustrating means for connecting the same with a faucet of a lavatory or other bathroom fixture;

Fig. 2 is a view in cross-section, partly broken away, taken along line 2—2 of Fig. 1;

Fig. 3 is a similar view taken along line 3—3 of Fig. 1, and showing one form of device that may be utilized for controlling the filling and draining of the sitz bath and for maintaining the water therein at a fixed level during the desired soaking cycle;

Fig. 4 is a view taken along line 4—4 of Fig. 3;

Fig. 5 is a view taken along line 5—5 of Fig. 4;

Fig. 6 is a view similar to that of Fig. 3, but illustrating another embodiment of the invention;

Fig. 7 is a cross-section taken along line 7—7 of Fig. 6;

Fig. 8 is a view taken along line 8—8 of Fig. 6;

Figs. 9 and 10 are fragmentary views similar to Fig. 6, showing the water-flow control means thereof in other positions;

Fig. 11 is a plan view, with portions broken away, illustrating still another embodiment of the invention;

Fig. 12 is a fragmentary cross-sectional view taken along line 12—12 of Fig. 11;

Fig. 13 is a similar view taken along line 13—13 of Fig. 12;

Fig. 14 is a fragmentary view, partly in elevation and partly in cross-section, showing one form of anti-siphoning device that may be employed in conjunction with the invention; and

Fig. 15 is a view in cross-section, taken along line 15—15 of Fig. 14.

Referring now in more detail to the drawings, numeral 10 designates a conventional toilet bowl having an upper portion 11 with an inwardly extending rim 12 which has its uppermost surface 13 disposed in a substantially horizontal plane, though rounded off at the edges thereof, as shown. The conventional seat for the toilet bowl, usually hinged adjacent the rear end of the toilet bowl, is not illustrated in the drawing. The sitz bath of the invention is preferably designed to be supported in its operative position on the uppermost surface of the bowl, with the seat in fully raised position away from the bowl. However, the sitz bath may be configured and dimensioned so as to be selectively supported either on the seat or on the rim of the bowl.

In the embodiment of the invention illustrated in Figs. 1 to 5, the sitz bath proper, indicated generally by numeral 20, comprises a basin made of stainless steel, aluminum, or other suitable metal, or of molded synthetic plastic resin of suitable type, porcelain or enamel ware, or, in certain instances, of molded fibrous material.

The basin is preferably oval shape in its horizontal configuration, and is dimensioned so that its side wall 22 will fit more or less loosely within the rim 12 of the toilet bowl.

The side wall 22 preferably extends inwardly at a slight angle toward the bottom 23. At its upper margin, the basin is formed with a horizontal outwardly extending flange 25, desirably extending around its entire perimeter, and terminating in a rounded edge 26. The transverse dimension of flange 25 from the upper end of side wall 22 to the edge 26 will be such as to enable the basin to be supported by the rim 12 of any of the several standard sized toilet bowls so as to retain the basin in its operative position on the rim of the toilet bowl and yet permit it to be readily lifted from operative position.

In order to provide for the admission of water into, the drainage of water from, and maintenance of water at a fixed level for the necessary period of time within, the basin, by means associated directly with the basin and in the easy reach of the user, the basin is formed at its forward end with a relatively small open pocket or the like

27. The sides 30 of the pocket are integral with the flange and extend downwardly therefrom preferably at a slight inward angle along the exterior of the front wall of the basin. The pocket 27 may extend a distance of several inches on each side of the major axis of the basin. A guide slot or opening 32 extends through the flange 25 and into the pocket, this opening being relatively elongated in the direction transverse to the major axis to the oval shape of the basin, and located symmetrically with respect thereto. Thus, guide slot 32 will be positioned between the thighs of a patient seated on the basin with the legs of the patient spread slightly apart. An opening or openings 33 are formed in the wall of the basin at a suitable distance below its top, and serving as an overflow discharging directly into the toilet bowl to maintain a uniform level of water in the basin.

Disposed for rotary actuation within the pocket 27 is a valve plate 35 mounted on a pivot 36 fixed to the front of the basin. The valve plate 35 is formed with an internal passageway 39, one end of which terminates at the upper edge of the plate, where it is threaded or otherwise formed to receive one end of a fitting 40 extending through and movable from side to side in opening 32. The opposite end of the passageway 39 terminates at the inner face of the plate adjacent its lower end. Formed in the front wall of the basin is an opening or port 41

of a size corresponding approximately to the cross-sectional dimension of passageway 39. Port 41 is located adjacent the bottom of the basin and with its axis displaced at an acute angle with respect to a vertical axis through the pivot 36. Thus, when the valve plate 35 is in the full line position shown in Fig. 4, water entering through connection 40 will by-pass the port 41 and discharge into the toilet bowl through pocket 27. When the valve plate 35 is rocked on its pivot to the position indicated in dotted lines at the right of Fig. 4, the inner end of passageway 39 coincides or registers with the port 41, thereby enabling water flowing through connection 40 to pass directly into the basin. When the valve plate 35 is rocked on its pivot in the opposite direction from the full line position to the other dotted line position shown in Fig. 4, the contents of the basin will drain out through port 41 directly into the toilet bowl, while at the same time water flowing through the valve will discharge directly into the toilet bowl through pocket 27.

Water may be fed to the basin through the valve device described, by means of a flexible hose 45, having one end attached to the outer end of the fitting 40, and its opposite end connected to the faucet of a lavatory or other conventional bathroom fixture.

The patient seated on the flange of the basin will thus have the water feed control conveniently located between his or her thighs. By grasping the fitting 40 between the fingers of the hand and rocking it sidewise in one direction or the other to rotate valve plate 35, the patient may readily and selectively control the initial filling of the basin, the continued introduction of water into the basin, or its by-passing directly to the toilet bowl during the soaking period, and also its drainage therefrom at the conclusion of the soaking period.

As will be observed, the construction is such as to provide for the introduction of the water into the basin at a point adjacent its bottom. This serves to promote the rapid mixing of incoming water with the water already in the basin, avoids direct impingement of a stream of water upon the buttocks of the patient, and enables the body of water in the basin to be kept in a state of motion. At the same time, it avoids splashing of any water over the top of the basin and onto the clothing of the patient.

In the embodiments of Figs. 1 to 5, the valve means 35 extends along the wall of the basin adjacent the front end thereof, in which case the fitting 40 would be suitably modified for connection with and manipulation of the valve means to control flow of water into and out of the basin through suitably located ports formed in its bottom.

In the embodiment of Figs. 6 to 10, the basin is formed centrally of its front end with a cylindrical boss 50 on its exterior. The boss 50 accommodates an elongated valve member 51 extending from adjacent the bottom of the basin and through a circular opening in the flange 25, to a point above the flange, for rotatable movement on its longitudinal axis. A longitudinal passageway 52 extends centrally through member 51, the inner or discharge end of the passageway coinciding with an opening 53 extending through the side wall of the basin. As will be noted, the opening 53 is located at a short distance above the bottom of the basin. Below the opening 53, and immediately adjacent the bottom of the basin, another opening 55, preferably vertically elongated, and serving as a drainage opening, is formed in the side wall of the basin. Desirably, the bottom wall of the basin is formed at the front end thereof with a lug or extension 56 serving as a bottom rest to limit downward movement of the valve. The lower end of valve member 51 is chamfered or bevelled, as indicated at 57, this surface 57 being displaced about 90 degrees from the discharge end of passageway 52. In the position of the valve 51 shown in Fig. 6, water flowing through the passage-

way 52 enters the basin through the opening 53. When a desired level of water in the basin has been attained the valve may be rotated approximately 90 degrees from the position shown in Fig. 6 to the position shown in Fig. 10. In that position, water flowing through the passageway 52 will discharge directly into the toilet bowl. At the conclusion of the soaking period desired by the patient, valve 51 may be rotated approximately 180 degrees from the position shown in Fig. 10 to the position shown in Fig. 9. In the latter position of the valve, water flowing through passageway 52 will continue to discharge directly into the toilet bowl, while at the same time, the contents of the basin are permitted to drain directly into the toilet bowl through the drainage opening 55 by way of the space between the latter and the surface 57.

For manipulating the valve, a suitable handle portion 59 may be formed at the upper end thereof. As will be understood, the upper end of the valve may be suitably formed for connecting the same with a flexible hose 45 leading from a lavatory faucet.

In the embodiment of the invention illustrated in Figs. 11 to 13, the basin is formed at its front end with an external compartment 60 extending from the flange 25 down to the bottom of the basin, bottom wall 61 of the compartment being formed as an extension of the bottom wall 23 of the basin. The top wall 62 of the compartment, comprising a portion of the flange 25, is formed with a central, relatively elongated opening 63 to receive for sliding or swinging movement a suitable fitting 64 connected with the outlet end of a flexible hose. Extending upwardly from the bottom wall 61 of the compartment is a partition 65, disposed preferably in the plane of the major axis of the basin to divide the compartment into sides A and B. Spaced from one side of the partition, at a short distance below the top thereof, the wall of the basin constituting the inner wall of the compartment is formed with an opening 66. Another opening 67 is provided in this wall of the basin immediately adjacent the bottom wall 23, and spaced a short distance from the opposite side of partition 65. An opening 68 is also formed in the bottom wall 61 of the compartment on the same side of the partition as that on which opening 66 is formed. Thus, water flowing through the hose into side A of the compartment will flow through the opening 67 into the basin proper to the level of the opening 66, excess water overflowing therethrough into side B of the compartment to be discharged through the drainage opening 68 into the toilet bowl. By sliding the fitting 64 along the length of the opening 63, or by simply rocking it therein from one side of the partition to the other, the flow of water may be diverted from one side of the partition to the other.

In this embodiment, as will be noted, the gap between the outlet end of the hose or fitting, and the highest level of water serves effectively as an anti-siphoning means to prevent back-siphoning of water from the sitz bath to the water supply system, as is required by the sanitary codes in many communities.

In lieu of the elongated opening 63 for enabling the discharge end of the hose or the fitting 64 to be slid or rocked for directing the water to either side of the partition 65, a circular opening may be employed so as to hold the hose or fitting in a substantially fixed position. In that case, the water flow may be directed to one side of the compartment or the other by means of a baffle or deflector plate in the compartment, and pivoted to the outer wall of the basin at a suitable location adjacent the upper end thereof.

Reference has been hereinabove made to the sanitary codes in many communities with regard to connecting plumbing fixtures to the water supply system. It is another advantage of the present invention that in embodiments thereof such as illustrated in Figs. 1 to 10, suitable anti-siphoning devices may be interposed between the

inlet of the flow control valves described and the water faucet. One such device is illustrated at 70 in Figs. 14 and 15. This may comprise a relatively flexible cone-shaped or funnel-like member 71 formed on its exterior surface with a plurality of longitudinally extending flutes or ribs 72 at the lower end thereof and extending into the upper end of an outer member 73, the lower end of which is suitably formed for detachable engagement with the valve member of the flow control means. Thus, by attaching the upper end of member 71 to the fitting at the discharge end of the flexible hose, and attaching the lower end of member 73 to the inlet end of the valve, the anti-siphoning device 70 will prevent any excessive pressure that may build up within the valve member or its connection to the sitz bath, from causing a back-flow of water in the direction of the faucet, since the interior of the member 73 is in direct communication with the atmosphere by way of the space between the opposed surfaces of members 71 and 73. By arranging the device 70 so that the point at which its upper end is connected with the hose outlet is at a distance of at least one inch above the top of the basin, the arrangement would comply even with the most restrictive sanitary codes in effect in certain communities. Manifestly, other suitable forms of anti-siphoning devices may be similarly employed in connection with the sitz bath constructions embodying the invention.

As above indicated, the sitz bath may be made of various materials, including suitable metals, molded synthetic plastic resins, porcelain or enamelware, and molded fibrous material. For use in hospitals, stainless steel would in most cases be preferred, principally because of the necessity for sterilizing the sitz bath after use by each patient. For use by the patient at home, less costly material would obviously be preferred. Particularly with that in view, it is an advantage of the invention that the sitz bath may be molded from synthetic plastic resins of commercially available types. Indeed its structure and configuration are such as to enable it to be produced by the more recently developed and relatively inexpensive vacuum molding process. Thus, the sitz bath of the invention may be produced at sufficiently low cost to make it available to patients of even low income, for use at home during the period of the post-operative treatment required after undergoing a hemorrhoidectomy or like surgery as referred to above. Indeed, it may be sufficiently low in cost to the patient to warrant discarding it after full recovery. The construction of the sitz bath also lends itself to the utilization of molded fibrous material, impregnated with waterproof material, to provide a sitz bath at a cost sufficiently low to be disposed of after a single use.

What is claimed is:

1. A sitz bath for the purposes set forth, comprising a basin formed at its upper perimeter with an outwardly extending flange for supporting the basin on the rim of a toilet bowl and with the body of the basin suspended within the bowl, said basin having an inlet opening and a drainage opening formed therein adjacent the bottom of the basin, and flow control means mounted on the outer surface of said basin for selectively supplying water at a regulatable rate to the basin through said inlet opening or for by-passing said inlet opening whereby water from said flow control means will discharge directly into the toilet bowl or for draining said basin through said drainage opening.

2. A sitz bath for the purposes set forth, comprising a basin formed at its upper perimeter with an outwardly extending flange for supporting the basin on the rim of a toilet bowl and with the body of the basin suspended within the bowl, said basin having an opening adjacent the bottom thereof, and flow control means mounted on the outer surface of said basin for selectively supplying

water at a regulatable rate to the basin through said opening or for by-passing said opening whereby water from said flow control means will discharge directly into the toilet bowl, or for draining said basin through said opening.

3. A sitz bath as defined in claim 1, wherein said flow-control means comprises a valve device, and wherein said flange has an opening therein, said valve device having operating means therefor extending through said flange opening.

4. A sitz bath as defined in claim 1, wherein said flow-control means comprises a valve plate rotatable on a pivot fixed to the wall of said basin.

5. A sitz bath as defined in claim 2, wherein said flow-control means comprises a movable member having a passageway extending therethrough, and means connected to said flow control means and disposed above said flange for moving said member to bring the outlet end of said passageway into or out of registry with said opening.

6. A sitz bath as defined in claim 1, wherein said basin is oval-shaped and wherein said flow-control means is disposed at one end thereof, said flange having a relatively elongated opening formed therein at said end of the basin, the longitudinal dimension of said flange opening being disposed transversely of the major axis of the basin.

7. A sitz bath as defined in claim 3, wherein said basin is oval-shaped and wherein said valve device comprises a plate member pivoted to the wall of said basin, said plate member having an internal passageway, the outlet end of said passageway being positioned to coincide with said inlet opening when said member is rotated to a predetermined position.

8. A sitz bath as defined in claim 7, wherein said valve device includes means to move said member to a position at which the outlet end of the passageway does not coincide with said inlet opening.

9. A sitz bath for the purposes set forth, comprising a basin formed at its upper perimeter with an outwardly extending flange for supporting the basin on the rim of a toilet bowl and with the body of the basin suspended within the bowl, said basin having an opening adjacent the bottom thereof, and flow-control means formed with said basin, said flow-control means comprising a compartment on the exterior of said basin, a vertically extending partition in said compartment, said opening being disposed on one side of said partition, an opening in the wall of said basin adjacent the top of the basin and on the opposite side of said partition, to serve as an overflow from the basin to the compartment, and a drainage opening at the bottom of said compartment on said opposite side of said partition, whereby over-flow from the basin will discharge directly into the toilet bowl.

10. A sitz bath as defined in claim 1, wherein said flow-control means comprises a valve device operable by handle means adjacent the top of the basin, the inlet of said valve device being connectable to one end of a flexible conduit having its opposite end connected to a water faucet, and wherein an anti-siphoning means is interposed in said conduit between the faucet and the valve device to prevent backflow from said valve to said faucet, said last-named means having its connection with said conduit at a distance of at least one inch above the top of the basin.

11. A sitz bath as defined in claim 1, wherein said flow-control means comprises a cylindrical boss on said outer surface of the wall of said basin and a valve member rotatable on its axis in said boss.
